PLAYING CARD SHUFFLER

Earl Morgan and Ellie M. Rosecrans, Kansas City, Mo.

Application April 10, 1950, Serial No. 155,052

1 Claim. (Cl. 273—149)

This invention relates to improvements in playing card shufflers and has particular reference to a card shuffler suitable for shuffling a larger number of cards than is in the present playing card deck.

Certain card games such as canasta require the use of plurality of decks of cards, which, due to their number are very unwieldy for most players who need a mechanical device to quickly and properly shuffle said cards.

The principal object of the present invention is the provision of a pair of gear segments operatively mounted on a base member, means carried by each of said gear segments for carrying a pack of cards in radial relation with said gears, and detents carried by said base member in the path of travel of the free ends of said card packs, whereby when the gears are properly rotated said packs of cards will be properly shuffled.

Other objects are simplicity and economy of construction ease and accuracy of shuffling and adaptability for use for shuffling cards of various sizes and numbers.

With these objects in view as well as other objects which will appear during the course of the specification reference will be had to the drawings wherein:

Fig. 1 is a plan view of a playing card shuffling device with the parts in position for receiving the card packs for shuffling and embodying this invention.

Fig. 2 is a side elevational view of the card shuffling device shown in Fig. 1.

Fig. 3 is a cross sectional view taken on line III—III of Fig. 1.

Fig. 4 is an enlarged fragmentary plan view of the shuffling device shown in Fig. 1 with the parts shown in the shuffling position in solid lines and in the shuffled position in dotted lines.

Fig. 5 is an enlarged sectional view taken on line V—V of Fig. 1.

Throughout the several views of the drawings like reference characters refer to similar parts and the numeral 10 designates a base member of substantially inverted dish like cylindrical form having annular, outer flange 12 and a substantially planar base plate 14.

Two segmental gear members 16 and 18 are axially pivoted by bolts 20 to base plate 14 with their teeth 22 intermeshed in such a manner as to always maintain the rate of relative rotation of the two segmental gears 16 and 18 constant, so that if one of the gears is moved through a certain angle the other will simultaneously move through a like angle. Referring to Fig. 1 it will be noted that at each end of the toothed section of the gear segment there is a blank section 24 and likewise segment 18 has blank sections 26 at each end of the toothed section.

These blank sections 24 and 26 are so positioned that they engage each other to limit the rotatory movement of the gear segments in both directions as the device is operated to shuffle the cards.

Mounted on a radial line adjacent the outer edge of gear segments 16 and 18 is a channel shaped pocket member 28 which is adapted to receive the end portions

2

of a deck of playing cards with the other end portions of the cards normally extending radially therefrom so as to be flipped as hereinafter set forth. These pocket members 28 are so related that when they are moved into aligned relation they will lie in a plane including the axes of pivot bolt 20 as shown in solid lines in Fig. 4. When in this position it will be noted that the main portions of one of the decks of cards will be bent rearwardly with their outer extremities contacting the spring detent 30 and that the outwardly projecting portions of the other deck of cards will contact the other spring detent 32. These detents are joined together at 34 and are provided with a vertical standard 36 by means of which they are secured to base 14. These spring detents are made of flat spring steel and are spaced above the top edge of segmental gears 16 and 18 and are symmetrically positioned relative to a line perpendicular to the center of the line joining the axis of the bolts 20. The free ends of detents 30 and 32 are rounded at 38 as shown in Fig. 3 to facilitate proper contact with the center line of the deck of cards which rest on platform 40 thus supporting the outer portion of the deck of cards above the surface of the gear surfaces. It will be noted that the platform 40 extends inwardly from the pocket member beyond the center of the deck and transversely thereto so as to serve to support the outer portion of the cards at all times during the shuffling operation.

Referring to Fig. 2 it will be seen that the standard 36 has a horizontal top 42 disposed at a right angle to the junction 36 of members 30 and 32, to present a support for one deck of cards by means of which the entire group of cards, which usually contains two decks, may be equally divided by placing one side of group against line 34 to support half the cards on top 42 while the other half is permitted to separate and move downwardly along the outer wall of standard 36 to cause the desired separation of the two decks.

A spring stop member 44 mounted on base 10 is disposed in the path of travel of the overlapping ends 46 of playing cards to hold them in condensed form as shown by dotted lines in Fig. 4 when all the cards have been flipped to the shuffled position.

The operation of this device is substantially as follows. The operator takes the entire group of playing cards to be shuffled, places them transversely against the joint 34 to rest on the top 42 of standard 36 whereby the cards are equally divided into two packs 48 and 50.

The device is positioned with its parts arranged as shown in Fig. 1 with the pocket members 28 positioned to receive the card packs 48 and 50 as shown. The gear stop blanks 24 and 26 at adjacent ends of the gear teeth stop the gear rotation in one direction. The card packs are now snugly fitted into pocket members 28 and the operator grasps the two pocket members with his two hands and forces the ends of the card packs 48 and 50 respectively against spring detents 30 and 32. Sufficient force is exerted by the operator to slightly compress the detents so as to cause a flipping of each card as it leaves the detents. With the cards properly divided in equal packs the cards will be alternately flipped from the two packs to take the positions shown in Fig. 5 at 46. That is with the end portions of the two packs interdigitated so that they may be removed from the device and manually bunched together in the usual manner. This operation may be repeated as many times as desired.

To prevent damaging of the machine the blank stops 24 and 26 come into contact after the cards have all been shuffled to prevent further movement of the gear members in the shuffling direction.

To facilitate easy insertion of the packs of cards into the pocket members it will be noted that the edges of the pockets have been flanged outwardly at 52.

3
While it has been suggested that the operator grasp and turn both of the pocket members to shuffle the cards, it is quite apparent that with the gear construction as described the movement of one of the gear members will cause a corresponding movement of the other gear member, and that the operator hence actually need grasp and turn only one of the pocket members.

What we claim as new and desire to protect by Letters Patent is:

A card shuffling device comprising a base member, intermeshed gear members axially mounted on said base member, a pocket member rigidly fixed to each gear member and adapted to receive a pack of cards with their end portions extending outwardly therefrom, detents carried by said base in the path of travel of the end portions of

5
said cards, whereby as said gears are driven said cards will be shuffled, said gears each having integral, non-meshing terminal projections adapted to engage corresponding projections on the other gear member to stop rotation of the gear members.
